DESIGN FOR A RADIATOR GRILLE

John Oswald, Lansing, Mich., assignor to General Motors Corporation, Detroit, Mich., a corporation of Delaware

Application November 24, 1937, Serial No. 73,161

Term of patent 3½ years

To all whom it may concern:

Be it known that I, John Oswald, a citizen of the United States and a resident of Lansing, county of Ingham, and State of Michigan, have invented a new, original, and ornamental Design for a Radiator Grille, of which the following is a specification, reference being made to the accompanying drawings, forming a part thereof.

Figure 1 is a front elevational view of the novel radiator grille.

Figure 2 is a side view of Figure 1.
Figure 3 is a partial sectional view on the line 3—3 of Figure 2.

I claim:
The ornamental design for a radiator grille as shown,

JOHN OSWALD.
